WATER CLOSET FLUSHING APPARATUS
Richard Wendell Williams, Dix Drive, Blissman Acres,
East McKeesport, Pa.
Filed July 27, 1959, Ser. No. 829,876
8 Claims. (Cl. 4-37)

This invention relates to water closet valves. More particularly, this invention pertains to controls and valves for water closets which permit the user to select the volume of water used in the flush.

There have been certain apparatuses in prior use in the art which have sought to control the amount of water utilized in the flushing. In some instances, these apparatuses were designed to conserve the amount of water used in the flush. However, most of these apparatuses required major revision to the tank, valve seat, overflow pipe, or all of these, of the standard water closet.

With the general increase of population in certain metropolitan areas and the resultant lowering of the water table in those areas, it has become increasingly more important to conserve water. It is, of course, desirable to accomplish this, if possible, without inconvenience to the inhabitants of these areas. Toward this end, I have conceived the invention disclosed herein, which is embodied in an apparatus which may be installed quickly and easily in the tank of a standard water closet or may be included as part of the equipment upon the initial installation.

I have found that a very small amount of water need be released from the tank of a water closet to accomplish a change of the water in the bowl when there is no solid matter in the bowl. It will be obvious that an important economy can be wrought through the use of my apparatus, in view of the many instances when it is required to flush the water closet even though there is no solid matter in the bowl.

Briefly, to describe my invention, I provide a basically cylindrical housing which, in installation, is superimposed over and around the standard valve seat in the tank of a water closet and stands approximately parallel to and adjacent to the standard overflow pipe of the water closet. The said housing is open at both of its ends and is held in place by the standard guide member which clamps onto the overflow pipe. On the side of the said housing, approximately opposed to the side adjacent to the overflow pipe, I provide a gate valve which is hinged at its upper extremity, so as to open inwardly into the said housing. A vertically operated lock rod is slidably engaged in the housing, in a position to restrictively engage the said gate valve on its inward side and is indirectly connected to the flush operating lever for lifting into a position of disengagement when it is desired to fully flush the water closet. When my apparatus is installed in a standard water closet, I provide an extension for the flush operating lever to which the lock rod is indirectly connected. The standard buoyant ball valve is enclosed within the cylindrical housing and, insofar as it seats and unseats in the standard valve seat, operates in the usual manner. The stem of the said buoyant ball valve passes through the aforementioned standard guide member and is connected indirectly and resiliently to the flush operating lever. I provide a basically cylindrical sleeve which slidably engages the cylindrical housing on the inside thereof and is adjustably positioned to extend above the upper extremities of the said housing. The said sleeve rests upon the said standard guide member and its vertical adjustment to accommodate for different tank water levels is accomplished by slots of different depth which I provide in its lower extremity. By merely rotating the sleeve until a particular slot is positioned over the standard guide member and lowering it thereupon, the vertical adjustment and the positioning

2

of the sleeve is simply performed. A flat, thin, circular baffle plate surrounds the stem of the buoyant ball valve, rests upon the standard guide member and has a diameter somewhat smaller than the inside diameter of the sleeve so that it fits very loosely therein. A resilient coupling, in the order of a helical spring, is provided between the standard valve stem and the standard lift rod therefor, for the purpose of providing a resistance stop for the small flush or rinse by restricting the upward movement of the flush operating lever thereby providing a resilient stop. By applying additional pressure the helical spring is compressed and additional upward movement to the flush operating lever is provided to lift the lock rod out of engagement with the gate valve. Thereupon, the gate valve is opened by the water pressure in the tank and sufficient water flows into the bowl to accomplish a full flush.

It is important, to the novelty of my invention, to notice that it is actually advantageous to the operation of my apparatus for the tolerances of fit; as for example, around the bottom of the housing, around the gate valve, around the lock rod and between the sleeve and the housing, to be quite large. This is so for the reason that it is necessary, on the partial flush operation, for there to be a certain flow of water beneath the ball valve to preserve its buoyancy. It should be noted, in this respect, that I have provided a slot in the lower extremity of the housing to allow clearance for the standard saddle connecting the valve seat and the overflow pipe. Neither this slot nor the slots which provide clearance for the standard guide member need be of exacting tolerance or a close fit.

To explain the operation of my apparatus, upon installation the sleeve is adjusted as aforementioned by positioning one of the slots over the guide member. The particular slot which is chosen will depend, in each installation, upon the water level which the standard float shut-off valve normally maintains in the tank. When the tank is filled to the upper limit permitted by the float shut-off valve, the upper extremity of the sleeve must be below the water level, and the distance below the water level is determined by experimentation to discover the least amount of water required to change the water in the bowl. When the flushing lever is operated for the partial flush, the ball valve is drawn free of the valve seat, the helical spring resiliently restricts full upward movement of the flush operating lever and water flows over the top of the sleeve and strikes the baffle plate which deflects the water to the sides of the sleeve and housing so that it will not strike the top of the ball valve and force it into a seated position before the flush is complete. During this operation, water also flows through the loose fits around the gate valve and the bottom of the housing, thereby supplementing the supply of water below the ball valve to preserve its buoyancy until the operation is complete. The gate valve remains closed during the partial flushing operation. When the water level has dropped to approximately the top of the sleeve, there is no longer sufficient water beneath the ball valve to maintain its buoyancy and it re-seats in the normal manner to complete the operation. Thereupon, the float shut-off valve permits the water level to return to the full position, as in the standard installations now extant in the art.

When the flushing lever is operated for the full flush, the ball valve is drawn free of the valve seat, the flush operating lever is moved to its uppermost limit, the lock rod is lifted and disengaged from the gate valve, the force of the flowing water opens the gate valve inwardly and the tank empties. Thereupon, the ball valve re-seats, the gate valve drops into closed position, the lock rod re-engages the gate valve to lock it closed, and the standard

float shut-off valve permits the water level to return to the full position.

It will be obvious that the operation of my apparatus can be accomplished with the standard flush lever, merely by the operator becoming accustomed to the feel of the two (2) different operations. However, where it is thought advisable to provide more positive operation, I have provided a dual handle for the flushing lever which accomplishes a positive operation of my apparatus, even by one unfamiliar with its function. This novel handle is shown in the drawings and explained hereinafter.

One object of my invention is to provide a flushing apparatus which will accomplish a saving of water in the use of water closets. Another object of my invention is to provide such a flushing apparatus which may be installed readily and easily in standard water closet installations without major revision thereto. Further and additional advantages of my invention will appear from this specification and the appended claims.

Referring now to the drawings:

FIG. I shows a cut away elevational cross-section through the tank of a standard water closet with the apparatus embodying my invention installed therein and shown in the closed position with the water level in the tank in the filled position.

FIG. II shows an elevational cross-section through the apparatus embodying my invention and showing the apparatus in the position for the partial flushing operation.

FIG. III shows an elevational cross-section through the apparatus embodying my invention and showing the apparatus in the position for the full flushing operation.

FIG. IV shows a plan view of the tank of a standard water closet with the apparatus embodying my invention installed therein, and taken in the plane of section line IV—IV of FIG. I.

FIG. V shows an elevation of the apparatus embodying my invention and taken in the plane of section line V—V of FIG. II.

FIG. VI shows a cut away cross-sectional plan view through a novel handle which provides a more positive operation of the apparatus embodying my invention.

FIG. VII shows a cut away elevational cross-section through the novel handle, showing it in the unflushed position.

FIG. VIII shows a cut away elevational cross-section through the novel handle, showing it in the position for partial flushing.

FIG. IX shows a cut away elevational cross-section through the novel handle, showing it in the position for full flushing.

FIG. X shows a cross-section through the lever portion of the novel handle and taken in the plane of section line X—X of FIG. VII.

The numeral 1 indicates generally the tank of a standard water closet having a standard fixture therein comprising the flushing flow pipe 2, the valve seat 3 and the overflow pipe 4 having a standard guide fixture 5 engaged thereto. The numeral 6 indicates a standard flushing handle engaging a standard flushing lever 7. The numeral 8 indicates a basically open-ended cylindrical housing which surrounds the valve seat 3 and the standard ball valve 9 and is held in place by the guide fixture 5 which fits into a slot 10 in the upper extremity of the housing 8. The said housing 8 has a projection 8' disposed outwardly and having a gate valve 16 mounted in the side thereof. The sleeve 11 fits loosely into the housing 8 and has a plurality of variant depth slots 12 in its lower extremity which fit over the guide fixture 5. The stem of the ball valve 9 is resiliently engaged by means of the spring 14 to the standard lift rod 15 which cooperates with flushing lever 7 to raise the ball valve. The gate valve 16 in the housing projection 8' has a horizontal hinge 17 pivotally engaging it to the housing projection at the upper extremity of gate valve 16. The lock rod 18 engages the gate 16 in the closed position and is

slidably connected with lift rod 19 which cooperates with flushing lever 7 to lift the lock rod 18 for the full flushing operation. The lock rod 18 has a stop 20 thereon and is slidably mounted in a bore 21 in the housing projection 8'. A thin circular baffle plate 22 surrounds the valve stem 13 and rests on the guide fixture 5 in a circumferentially spaced relation with the inside of sleeve 11.

The water level in the tank is shown as point A for the full position, point B for the partial flush position, point C for the lowering position during the full flushing operation, and point D for the fully flushed position.

It will be understood that my invention may be installed in standard water closets wherein the standard type of flushing handle is employed. However, I also provide a novel dual flushing handle which provides a positive flushing operation for either a full flush or a small flush. In this portion of my invention, as shown in the drawings, the numeral 24 indicates the full flush

handle rigidly engaged to the extension of the flushing lever 7, which in turn is rotatably mounted in a mounting fixture 25. The said fixture 25 is mounted, in the usual manner, in the tank 1. The small flush handle 26 is rotatably mounted upon the body of the full flush handle 24. However, the rotation thereof is limited by the key slot 27 in the small flush handle 26 which loosely engages the key 28 on the full flush handle 24. Two stop lugs 29 on the mounting fixture 25 limit the rotation of the entire handle assembly by engagement with the key 30 on the body of the small flush handle 26.

In the operation of this handle assembly, downward pressure on the full flush handle 24 causes the key 28 to contact the upper limit of the key slot 27 and moves the key 30 into engagement with the upper stop lug 29.

This rotation provides the maximum movement to the flushing lever 7 and accomplishes a full flush. Downward pressure on the small flush handle 26 causes the lower limit of the key slot 27 to contact the key 28, thereby rotating the said key 28 and the flushing lever 7 in a limited amount until the key 30 contacts the upper stop lug 29. This amount of rotation accomplishes a small flush.

When the apparatus embodying my invention is installed in a standard water closet, I provide an extension 31 for the flush operating lever 7. The extension 31 is rigidly engaged to the said flush operating lever 7 by bolts 32—32, thereby extending the said lever 7 to facilitate the connection thereof to the lift rod 19.

Certain modifications of the embodiment of my invention shown in the accompanying drawings and described herein may be made within the scope of this specification and the appended claims without departing from the spirit of my invention.

I claim as my invention:

1. A water closet valve comprising a basically cylindrical open-ended housing having one end thereof disposed on the bottom of a water closet tank and surrounding the flush valve seat therein in substantially concentric spaced relation thereto, the said housing being disposed vertically upward therefrom to a height less than the normal full level of the tank in condition for flushing, a flushing lever positioned above the upper extremity of the said housing within the said water closet tank and communicating with a flushing handle mounted exteriorly of the said tank, a buoyant ball valve aligned with the said flush valve seat and being concentrically disposed within the said housing, a resilient mounting communicating with the said buoyant ball valve and having its uppermost extremity mounted on the flushing lever, and a gate valve pivotally mounted proximate the lower extremity of the said housing and opening inwardly thereinto.

2. A water closet valve according to claim 1 wherein a basically cylindrical sleeve is concentrically mounted within the upper extremity of the said housing in slidably

engagement therewith and extending thereabove, which said sleeve is vertically adjustable to extend more or less distance above the top of the said housing.

3. A water closet valve according to claim 1 wherein a locking means is mounted on the housing in engagement with the gate valve in closed position and communicates with the flushing lever whereby the said locking means is disengaged from the said gate valve upon full motion of the said flushing lever.

4. A water closet valve according to claim 1 wherein a baffle plate is mounted within the said housing in concentrically spaced relation thereto above the said buoyant ball valve.

5. A water closet valve comprising a basically cylindrical open-ended housing having one end thereof disposed on the bottom of a water closet tank and surrounding the flush valve seat therein in substantially concentric spaced relation thereto, the said housing being disposed vertically upward therefrom to a height less than the normal full level of the tank in condition for flushing, a flushing lever positioned above the upper extremity of the said housing within the said water closet tank and communicating with a rotating means mounted exteriorly of the said tank, buoyant closing means for the said flush valve seat disposed within the said housing, resilient lifting means communicating with the said buoyant closing means and having its uppermost extremity mounted on the said flushing lever, an orifice proximate the lower extremity of the said housing, and

variable restricting means for the said orifice whereby the said orifice may be opened or closed.

5 6. A water closet valve according to claim 5 wherein a locking means is mounted on the said housing in engagement with the said variable restricting means in closed position and communicates with the flushing lever whereby the said locking means is disengaged from the said variable restricting means upon full motion of the said flushing lever.

10 7. A water closet valve according to claim 5 wherein a baffling means is mounted within the said housing above the said buoyant closing means, which baffling means is adapted to deflect fluid toward the internal periphery of the said housing.

15 8. A water closet valve according to claim 5 wherein the flushing lever rotating means is comprised in a plurality of rotatably mounted handles adapted to effect individually distinct movements of the flushing lever.
